TYPEWRITER COMPANY, OF NEW YORK, N. Y., A CORPORATION OF DELAWARE.

TYPE-WRITING MACHINE.

1,062,835.

Specification of Letters Patent. Patented May 27, 1913.

Application filed May 7, 1912. Serial No. 695,754.

To all whom it may concern:

Be it known that I, JOHN C. McLAUGHLIN, a citizen of the United States, residing in Jersey City, in the county of Hudson and State of New Jersey, have invented certain new and useful Improvements in Type-Writing Machines, of which the following is a specification.

This invention relates to typewriting machines, and more particularly to means for operating from the space-key the escapement of the carriage feeding device.

In machines such as the Underwood writing machine, the feeding mechanism for the carriage usually embodies an escapement consisting of a toothed wheel co-operating with a pair of dogs mounted on a rocker. One of these dogs, known as the feed dog, is loosely mounted on the rocker, and is normally engaged by a tooth of the escapement wheel and held against a stop provided on the rocker. The other dog, known as the detent dog, is rigidly connected with the rocker and has a beveled face which engages the escapement tooth when the latter is disengaged from the feed dog by a movement of the rocker. In the usual form of typewriting machine, such as above mentioned, the rocker will be so moved or swung whenever a space-key is depressed. When the key is released, the rocker swings so as to free the escapement tooth from the detent wheel and allow the feed dog to engage the next tooth, the carriage thus being fed forward one space. This movement of the rocker is accelerated by the pressure exerted by the escapement wheel against the beveled face of the detent dog, thus making the escapement very sensitive. However, should the operator not release the space-key promptly, there is liability of one or more additional teeth escaping past the feed dog, and the carriage skipping one or more spaces. Moreover, in machines such as above described, the feeding operation has hitherto taken place during the upward movement of the space-key, thus necessitating the release of the space-key before another type-key can be operated. This, of course, tends against speed of operation.

The principal object of the present invention is to eliminate these difficulties, and to this end simple mechanism is provided which prevents the possibility of the escapement wheel skipping a tooth during the op-

eration of the space-key, and accomplishes this by causing the cycle of operation of the escapement mechanism to be completed during the down stroke of the space-key, and permitting the rocker to return promptly after being actuated to the limit of its movement. This prompt return of the rocker takes place irrespective as to whether or not the space key is kept depressed or is partially released by the operator. The mechanism provided for this purpose consists essentially of a relatively movable projection operatively connected with an arm extending from the space-bar, which projection engages a cam projection on the rocker carrying the dogs of the escapement mechanism. The space-key, instead of operating the rocker through the universal bar, as in the usual construction of typewriting machine, operates this rocker through the engagement of the projections above mentioned. When the space-key is depressed, the movable projection mounted on the arm extending from the space-key engages the cam projection on the rocker, cams the latter to one side, and then abruptly rides past the same allowing the rocker to promptly return. Thus the cycle of operation of the escapement mechanism is completed during the down stroke of the space-key, and the carriage is fed forward before the space-key is released. If the operator should then fail to release the space-key promptly, or, should he release it partially, it will have no effect on the escapement mechanism, as the latter has completed its cycle of operation and could not be affected by the movement of the space-key until the latter is entirely released and depressed again. Moreover, with the mechanism above described, it will be possible for the operator to operate another type-key before he releases the space-key.

Other objects and advantages will appear hereinafter.

In the accompanying drawings, Figure 1 is a longitudinal section elevation of a typewriter with the space-key and the improved connection to the escapement mechanism shown in normal position. Fig. 2 is a perspective view illustrating, in the position of parts shown in Fig. 1, the escapement mechanism and the means for operating it from the space-key. Fig. 3 is a fragmental view, similar to Fig. 1, illustrating, in an intermediate position, the rocker and the means

for operating the same. Fig. 4 is a fragmental detail view of the escapement mechanism in an intermediate position, with a tooth of the escapement wheel engaging the beveled face of the detent dog. Fig. 5 is an enlarged section taken about on line 5—5 of Fig. 4, and illustrating a position wherein the detent dog is partially in the path of a tooth of the escapement wheel.

- 10 The space-key 1 has extending therefrom on the other side of its fulcrum, an arm 2 having pivoted thereto adjacent its end a link 3, guided by a pin 4 fixed in a bracket 5 mounted on the frame of the machine. 15 Mounted on this link is a pivoted stop or projection 6, held from movement in one direction by a pin 7 fixed to the link. This stop or projection 6 has a beveled face 8 adapted to engage the beveled face 10^a of a cam projection 10 formed on rocker 9 of the escapement mechanism, and through this engagement swings the rocker when the space-key is depressed. The stop 6 is also provided with an abrupt face 8^b, which, after the rocker has 20 been actuated to the limit of its movement, is brought into substantial alinement with an abrupt face 10^b provided on the projection 10, as shown in Fig. 3. When the stop 6 rides past the beveled face 10^a of the projection 10 on the rocker, the latter is abruptly released and is free to return to its normal position.

30 The general construction of rocker 9 and the rest of the escapement mechanism is substantially similar to that employed in the usual type of Underwood writing machine now in use. This rocker has mounted thereon the detent dog 11, having the beveled face 12, and the loose or feed dog 13, which 35 a tooth 15 of the escapement wheel 14 normally engages and holds, in opposition to the tension of spring 17, against a stop 16 formed on the rocker. This spring is fastened to the loose dog at one end and extends obliquely therefrom to a point on the frame to which it is fastened, and exerts a 40 tension on the rocker, tending to swing it into normal position, and at the same time serves to pull the loose dog away from the stop when this dog is swung away from its 45 engaging tooth by the movement of the rocker. The usual universal bar 18 is attached to the rocker, and is operated by the type bars 19 through heels 20 formed thereon adjacent their fulcrum 21. The escapement wheel has associated therewith the usual pinion 22 meshing with the feed rack 23 of the carriage 24.

50 When the space-key is depressed, it raises 60 arm 2 and the link carrying the pivoted stop 6. The latter, with its beveled face, engages the cam projection on the rocker, and swings it into the position shown in Fig. 3, wherein the feed dog has released a tooth 65 which is in turn engaged by the beveled face

of the detent dog. Before the space-key reaches the bottom of its down stroke, the pivoted stop or projection rides past and abruptly releases the cam projection on the rocker, and the latter quickly returns to its normal position, allowing the carriage to feed forward one space. The abruptness of the release of the rocker is independent of the speed with which the operator depresses the space key. Thus, under no circumstances does the escapement wheel have sufficient time to skip past the feed dog, and it is assured that the tooth engaging the feed dog is the next adjacent tooth to the one previously released. The carriage must therefore feed along but one space at a time, and this movement of the carriage takes place before the space-key is released. When the latter is so released, the pivoted stop rides freely past the cam projection on the rocker and has no operative effect thereon. It will thus be clear that the operator can operate another type-key before releasing the space-key.

It will be noted that, in the construction above set forth, the space key, in its operation, does not actuate the ribbon feed.

Variations may be resorted to within the scope of the invention.

Having thus described my invention, I claim:

1. In a typewriting machine having key-operated types, a carriage, and an escapement mechanism therefor constructed to complete its cycle of operation during the return strokes of the type keys, the combination with a space-key, of independent devices operated by said space-key for both actuating and releasing the escapement mechanism during the down-stroke of the space-key.

2. In a typewriting machine, a carriage, escapement mechanism including a toothed wheel, a rocker, a feed dog and detent dog mounted on said rocker, said detent dog having a beveled face, a space-key, means connected to said space-key for swinging said rocker so as to release the toothed wheel from the feed dog and to cause it to engage the beveled face of the detent dog, said means releasing the rocker during the down-stroke of the space key.

3. In a typewriting machine, a carriage, escapement mechanism including a rocker, a feed dog and detent dog mounted on this rocker, the rocker having a projection formed thereon, a space-key, mechanism connected to said space-key and including a stop adapted to engage said projection and release it during the downward movement of the space-key.

4. In a typewriting machine, a carriage, a feed dog and detent dog mounted on this rocker, the rocker having a projection formed thereon, a space-key, mechanism connected

to said space-key and including a relatively movable stop adapted to engage said projection and release it during the downward movement of the space-key.

5. In a typewriting machine, a carriage, escapement mechanism including a rocker, a feed dog and detent dog mounted on this rocker, the rocker having a projection formed thereon, a space-key, mechanism 10 connected to said space-key and including a relatively movable stop, means for limiting the movement of the stop in one direction, said stop being adapted to engage said projection and release it during the downward 15 movement of the space-key.

6. In a typewriting machine, a carriage, escapement mechanism including a rocker, a feed dog and detent dog mounted on this rocker, the rocker having a projection 20 formed thereon, a space-key, mechanism connected to said space-key and including a pivoted stop, means for limiting the movement of said stop in one direction, said stop being adapted to engage said projection and 25 release it during the downward movement of the space-key.

7. In a typewriting machine, a carriage, escapement mechanism including a toothed wheel, a rocker, a feed pawl and detent pawl 30 mounted on said rocker, said detent pawl having a beveled face adapted to engage the teeth of said wheel, a space-key, an arm connected thereto, and a relatively movable stop mounted on said arm and adapted to 35 engage the rocker to actuate the same.

8. In a typewriting machine, a carriage, escapement mechanism including a toothed wheel, a rocker, a feed pawl and detent pawl mounted on said rocker, said detent pawl 40 having a beveled face adapted to engage the teeth of said wheel, a space-key, an arm connected thereto, a link connected to said arm, and a projection on said link adapted to engage the rocker to actuate the same.

45 9. In a typewriting machine, a carriage, escapement mechanism including a toothed wheel, a rocker, a feed pawl and detent pawl mounted on said rocker, said detent pawl having a beveled face adapted to engage the 50 teeth of said wheel, a space-key, an arm connected thereto, a projection or stop mounted on said arm, and a projection formed on said rocker and adapted to be actuated by the first named projection, one 55 of said projections being relatively movable to its supporting element.

10. In a typewriting machine, a carriage, escapement mechanism including a toothed wheel, a rocker, a feed pawl and detent pawl

mounted on said rocker, said detent pawl 60 having a beveled face adapted to engage the teeth of said wheel, a space-key, an arm connected thereto, a link connected to said arm, means for guiding said link, a pivoted stop or projection mounted on said link, and 65 a projection on said rocker, said pivoted stop being adapted to engage said projection on the rocker and release it during the downward movement of the space key.

11. In a typewriting machine, a carriage, 70 escapement mechanism therefor comprising a toothed wheel, a rocker, a feed dog and detent dog mounted on said rocker, the latter having a projection thereon, said projection having a beveled face and an abrupt 75 face, a space-key, an arm connected thereto, a stop operatively connected with said arm, said stop having a beveled face adapted to engage the beveled face of said projection to actuate the rocker, and an abrupt 80 face adapted to be brought into alinement with the abrupt face of said projection to abruptly free said rocker.

12. In a typewriting machine, a carriage, escapement mechanism therefor comprising 85 a toothed wheel, a rocker, a feed dog and detent dog mounted on said rocker, the latter having a projection thereon, said projection having a beveled face and an abrupt face, a 90 space-key, an arm connected thereto, a relatively movable stop operatively connected with said arm, said stop having a beveled face adapted to engage the beveled face of said projection to actuate the rocker, and an abrupt face adapted to be brought into 95 alinement with the abrupt face of said projection to abruptly free said rocker.

13. In a typewriting machine, a carriage, escapement mechanism therefor comprising 100 a toothed wheel, a rocker, a feed dog and detent dog mounted on said rocker, said detent dog having a beveled face adapted to engage the teeth of said wheel, said rocker having a projection thereon, said projection having a beveled face and an abrupt face, a 105 space-key, an arm connected thereto, a pivoted stop operatively connected with said arm, means for limiting the movement of said stop in one direction, said stop having a beveled face adapted to engage the beveled 110 face of said projection to actuate the rocker, and an abrupt face adapted to be brought into alinement with the abrupt face of said projection to abruptly free said rocker.
